[57] CLAIM

The ornamental design for a suspension unit for wheels of a vehicle, as shown and described.

DESCRIPTION

FIG. 1 is a top plan view of a suspension unit for wheels of a vehicle which embodies my new design;

FIG. 2 is a bottom plan view thereof;

FIG. 3 is an end elevational view, the end opposite being a mirror image thereof;

FIG. 4 is a front elevational view thereof;

FIG. 5 is a rear elevational view thereof;

FIG. 6 is a perspective view of the top, rear and one end thereof;

FIG. 7 is a perspective view of the top, front and end thereof opposite to that shown in FIG. 6; and

FIG. 8 is a perspective view of the bottom, rear and end thereof shown in FIG. 6.

FIG.1.

FIG.2.

FIG.3.

FIG.4.

FIG.5.

FIG.6.

FIG.7

FIG.8
